US0D1063410S

(12) **United States Design Patent** (10) **Patent No.:** **US D1,063,410 S**
(45) **Date of Patent:** **** Feb. 25, 2025**

(54) **VANITY MIRROR**

(71) Applicant: **simplehuman, LLC**, Torrance, CA
(US)

(72) Inventors: **Frank Yang**, Rancho Palos Verdes, CA
(US); **Tzu-Hao Wei**, Hacienda Heights,
CA (US); **Daniel Ballou**, Long Beach,
CA (US)

(73) Assignee: **simplehuman, LLC**, Torrance, CA
(US)

(**) Term: **15 Years**

(21) Appl. No.: **29/875,913**

(22) Filed: **May 12, 2023**

& Bear, LLP

(57) **CLAIM**

The ornamental design for a vanity mirror as shown and described.

DESCRIPTION

FIG. 1 is a top, front, left-side perspective view of a vanity mirror embodying our design in a first state;

FIG. 2 is a top, rear, right-side perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof, and,

FIG. 8 is a bottom plan view thereof.

All features in broken line form no part of the claimed subject matter.

1 Claim, 6 Drawing Sheets
